UNITED STATES PATENT OFFICE.

EDWARD C. HOFFMANN, OF ST. LOUIS, MISSOURI.

COOKING RANGE.

Application filed December 24, 1925. Serial No. 77,443.

This invention relates to improvements in cooking ranges and consists in the novel construction hereinafter disclosed.

An object of the invention is to provide a range having a sheet metal body with a multiple ply lining including liner plates so designed as to form air pockets adjacent to the inner surface of a portion of the body, with a layer of material such as asbestos to insulate the body against heat, and a retaining plate for the lining provided with air pockets.

Another object of the invention is to provide in a range, a multiple ply lining that is effective for insulating the body of the range to protect the body against heat, and, at the same time, preventing rusting out or deterioration of the metallic walls of the body.

Additional advantages of the construction will be apparent from the following detailed description thereof, taken in connection with the accompanying drawing, in which,

Fig. 1 is a vertical section through the range;

Fig. 2 is a cross section on the line 2—2 of Fig. 1;

Fig. 3 is a vertical section through a portion of the lining on an enlarged scale;

Fig. 4 is a face view of one of the liner plates; and

Fig. 5 is a face view of one of the retaining plates.

In the embodiment of the invention illustrated in the drawing, which it will be understood is only a preferred illustration, the invention being applicable to all classes of stoves, the particular range illustrated is of the leg type of range comprising a base 1 supported by legs 2. The range body 3 comprises outer casing bottom and side walls of sheet metal, either sheet iron or sheet steel. Within the body near one side is the fire box 4 which is separated from the ash box 5 by grates 6, the sides of the fire box being provided with the usual liners 7.

Adjacent to and extending laterally from the fire and ash box section of the range is a rectangular sheet metal oven 8, which is spaced from the walls of the housing so as to provide around the top end and bottom wall thereof, and in the space between the same and the range body, a smoke flue which communicates with the smoke pipe 9 through an opening in the back of the range body.

A continuous passage of the product of combustion through the flue of the range results in a condition which deteriorates that portion of the outer metallic wall of the range which forms the exterior wall of the flue. Moreover, the heat from the flue normally desired for the heating of the oven is dissipated, unless the exterior flue walls are satisfactorily heat insulated.

The practice of heat insulating the exterior walls of the flue have been employed, asbestos being used in some instances for that purpose. But in the present construction, additional heat insulation is provided by the multiple ply lining for the flue by forming air pockets between the interior surface of the range body and a liner plate, and also providing an internal retaining plate having air pockets therein.

The lining is made of convenient sections. In the embodiment shown, the back wall of the flue is lined by a section 10 disposed horizontally from the edge of the smoke pipe to a point spaced from the end wall of the range, so as to accommodate a vertical section 11 extending to the bottom wall of the range. Another horizontal section 12 meets the vertical lower edge of the section 11 and extends transversely of the range to the edge of the smoke pipe near the bottom.

The outer side wall of the flue has another section 13 which may be made in more than one division if desired. Along the bottom wall of the flue is a section 14 which meets a vertical section 15 that extends from front to rear of the range. In practice, there will be another section corresponding substantially to the section 12 located against the front wall of the range body to complete the front lining for the flue in a plane parallel to the plane occupied by the section 12.

It will be noted that the left end wall of the oven has an extension 16 against which the section 15 abuts, closing the end of the flue and directing the products of combustion rearwardly into the opening to the smoke pipe. The bottom wall of the ash box also has a liner section that is formed substantially as are the liner plates for the flue liner.

The multiple ply liner comprises a liner plate 17, one of which is shown in detail in Fig. 4, from which it will be understood to comprise a suitably dimensioned plate having a marginal flange 18, a series of spaced vertical flanges 19 and one or more trans-

verse flanges 20. The flanges form a series of air pockets and the edges of the flanges are substantially in the same plane, so that the liner plate is fitted close against the inner wall of the sheet metal body of the range, forming air pockets between the exterior range wall, which pockets serve as dead air spaces preventing outward heat transfer and also preventing formation of moisture on the internal surface of the range body, thus providing against the rusting through of the walls of the range body.

The inner face of the plate 17 is smooth. A flat layer 21 of asbestos, or other suitable heat insulating material, is arranged to fit against this inner flat face of the liner plate 17. The heat insulating layer 21 serves to prevent heat transfer outwardly from the flue passage.

Against the inner face of the layer of heat insulating material is a retainer plate, as shown in Fig. 5, of which it will appear that it comprises an outer wall 22 having a series of depressions 23 in one face thereof. These depressions form air pockets when the retainer plate is assembled against the inner face of the layer of heat insulating material, as will clearly appear from Fig. 3, at being understood that the face of the plate 22 in which the depressions are formed lies adjacent to the layer of heat insulating material. The separate plies of the liner sections are secured together and the same are attached in place against the wall of the range body by bolts 24 that pass through registering openings in the range wall and in the separate plies of the liner sections, said bolts being equipped with nuts 25 on their inner ends.

That portion of the bottom wall of the range that lies beneath the ash box has a liner which is formed from a plate formed in the same manner as the liner plate 17, thereby forming air pockets that are sufficient without the use of the heat insulating layer to insulate the bottom of the ash box sufficiently to prevent scorching of the floor beneath the range at this area. This ash box liner is made of a separate section and bolted to the bottom wall of the range body by the bolts 24 having nuts 25.

I am aware that the construction may be modified without departure from the spirit and scope of the invention, and I do not limit myself to unessential details thereof. What I claim and desire to secure by Letters Patent is:—

1. A range having the outer body formed from sheet metal material, a liner plate having an inner flat face, and an outer face having air pockets formed therein, said outer face abutting against the inner face of the range body wall, a layer of heat insulating material disposed against the inner wall of said liner plate, and means for

retaining said elements together and in connection with the range body wall.

2. A range having the outer body formed from sheet metal material, a liner plate having an inner flat face, and an outer face having air pockets formed therein, said outer face abutting against the inner face of the range body wall, a layer of heat insulating material disposed against the inner wall of said liner plate, a retaining plate having air pockets formed in one wall thereof which abuts against the inner face of said layer of heat insulating material, and means for retaining said elements together and in connection with the range body wall.

3. A range having the outer body thereof formed of metallic walls, said range having a smoke flue, one wall of which comprises a portion of the outer body of the range, a plurality of liner sections for the portion of the range constituting the outer wall of the flue, each liner section comprising a layer of heat insulating material, a liner plate between the heat insulating material and the internal wall of the range body, said liner plate forming with the inner wall of the body a plurality of air pockets, and means for retaining the liner layers together and in connection with the range body.

4. A range having the outer body thereof formed of metallic walls, said range having a smoke flue, one wall of which comprises a portion of the outer body of the range, a plurality of liner sections for the portion of the range constituting the outer wall of the flue, each liner section comprising a layer of heat insulating material, a liner plate between the heat insulating material and the internal wall of the range body, said liner plate forming with the inner wall of the body a plurality of air pockets, an internal retaining member disposed against the inner face of the layer of heat insulating material, and means for retaining the liner layers together and in connection with the range body.

5. A range having the outer body thereof formed of metallic walls, said range having a smoke flue, one wall of which comprises a portion of the outer body of the range, a plurality of liner sections for the portion of the range constituting the outer wall of the flue, each liner section comprising a layer of heat insulating material, a liner plate between the heat insulating material and the internal wall of the range body, said liner plate forming with the inner wall of the body a plurality of air pockets, a retaining plate designed to abut against the inner face of the layer of heat insulating material, said retaining plate having recesses therein forming with the face of the heat insulating layer a plurality of air pockets, and means for retaining the liner layers together and in connection with the range body.

6. In a range, including outer metallic walls, an oven, a fire box arranged adjacent to the oven, an ash box below said fire box, a liner for that section of the range constituting the flue passage comprising a multiple ply structure having an intermediate layer of heat insulating material, and air pockets formed by said liner and the internal wall of the range and between said layer and the flue passage.

7. In a range, including outer metallic walls, an oven, a fire box arranged adjacent

to the oven, an ash box below said fire box, a liner for that section of the range constituting the flue passage comprising a multiple ply structure having an intermediate layer of heat insulating material, air pockets between said layer and the internal wall of the range and between said layer and the flue passage, and a liner below the ash box, said liner having spaced ribs forming walls of a plurality of air pockets between the wall of the range and said liner. 15 20

EDWARD C. HOFFMANN.
